UNITED STATES PATENT OFFICE

2,496,603

ROLLER TOY

Earnest L. Schwanengel, Dayton, Ohio

Application December 10, 1945, Serial No. 633,918

3 Claims. (Cl. 46—204)

1

This invention relates to improvements in roller toys and has for its object the provision of such a toy that may be easily rolled over floors, sidewalks and other smooth surfaces by children. The toy may be pushed or it may be pulled by means of a string suitably attached to some part of the frame.

These and other advantages will appear from the following description taken in connection with the drawings:

Figure 1 is a side elevation of the toy.

Figure 2 is a section on line 2—2 of Figure 1.

Figure 3 is a section on line 3—3 of Figure 2.

The main body of the toy consists of a frame formed by a pair of side members 1 and end members 2 suitably attached to each other. The frame is supported on rollers 3 which have suitable axles 4 extending through holes 4a therefore in the side members 1. Each of the axles 4 is provided with annular notches or grooves 5 which provide seats for a pair of floating discs 6. These discs 6 have no axles and no other means of support except the axles 4 and the axle 7. The axle 7 is supported in elongated holes 8 in the top of the side members 1. For the purpose of receiving the floating discs 6, the axle 7 is provided with two annular notches or grooves 9 similar in shape to the notches or grooves 5 located on axles 4. The axle 7 is entirely supported on the floating discs 6 but is guided in an up and down movement by means of the elongated holes 8 in the sides 1. On the axle 7 is a fly wheel 10. This fly wheel is rigidly attached to the axle 7 and rotates therewith. On the surfaces of the fly wheel 10 are color streaks as indicated by the numeral 11. These color streaks may be of various colors such as red, green or yellow.

For the purpose of operating the toy a string may be attached to either end of the toy whereby it may be pulled over any smooth surface. The rotation of the wheels 3 will cause the rotation of the axles 4. And the rotation of the axles 4 will cause the floating discs 6 to rotate. The rotation of the floating discs 6 will cause the axle 7 to rotate and the fly wheel 10 attached thereto.

What I claim is:

1. In a toy, a body composed of a pair of side members, a pair of axles rotatably mounted in the side members, said axles having wheels thereon extending below the side members for supporting said body, each axle having therein a

pair of annular grooves, a pair of floating discs resting on the axles in the grooves, a third axle rotatably mounted in the side members, said third axle having therein a pair of annular grooves, said third axle resting on the discs with one disc in each annular groove and a fly wheel fixed on said third axle.

2. In a toy, a body composed of a pair of side members, each side member having adjacent its lower edge a pair of holes and adjacent its top a vertically elongated hole, a pair of axles mounted in the lower holes, each axle having thereon a pair of wheels extending below the side members for supporting said body, each axle having adjacent each end an annular groove, a pair of floating discs resting upon the axles in the grooves, a third axle having a pair of annular grooves mounted for rotation and vertical movement in the upper holes, said third axle resting on the discs with one disc in each annular groove and a fly wheel fixed on said third axle.

3. In a toy, a body composed of a pair of side members, each side member having adjacent its lower edge a pair of holes and adjacent its top a vertically elongated hole, a pair of axles rotatably mounted in the lower holes and having thereon wheels extending below the side members for supporting said body, a pair of floating discs resting upon the axles, each floating disc being adjacent one side member, a third axle mounted for rotation and vertical movement in the upper holes, said third axle resting on the floating discs and a fly wheel fixed on said third axle.
